UNITED STATES PATENT OFFICE.

EDWIN P. KINGSBERRY, OF VALDOSTA, GEORGIA.

DESIGN FOR A HALL-RACK.

SPECIFICATION forming part of Design No. 32,043, dated December 26, 1899.

Application filed November 16, 1899. Serial No. 737,240 Term of patent 7 years.

To all whom it may concern:

Be it known that I, EDWIN P. KINGSBERRY, a citizen of the United States, residing at Valdosta, in the county of Lowndes and State of Georgia, have invented and produced a new and original Design for a Hall-Rack, of which the following is a specification, reference being had to the accompanying drawing, forming part thereof.

My invention has for its object the production of a design for hall-racks combining a new arrangement and configuration of the settee, side arms, and mirror centrally located upon a back frame and surrounded by advertising panels or spaces.

Referring to the accompanying drawing, which shows my hall-rack in perspective, the seat or settee 1 is provided with side arms 2. In front and below the seat are arranged ornamental panels, the upper one, 3, extending nearly the length of the seat. This panel is provided with handles, as shown, and forms the front of a drawer. Below are three other panels 4, extending in series across the front. At the back of the seat is a vertical back frame with side pieces 5, surmounted by a cornice 6 and head-piece 7 of ornate design. On the side pieces 5 are the hat and coat hooks 8, and below these, near the seat, are placed the um-

brella-hooks 9, provided with drip-pans 10, of which latter only one is shown. On the back frame, near the seat, are two ornamental panels 11, and in the space above these is centrally located an oblong mirror 12, vertically placed. Arranged around this are advertising panels or spaces intended for the reception and display of signs and the like, of which the upper and lower pairs 13 extend across the back between the side pieces 5. On either side of the mirror and between the upper and lower panels 13 are similar but shorter rectangular spaces 14, so that, as will be observed, the mirror is entirely surrounded by the advertising panels.

The cornice and head-piece capping the frame give to the whole a finished and artistic appearance, so that an attractive and beautiful, as well as useful, article of furniture is produced.

Having described my invention, what I claim as new, and desire to secure by Letters Patent, is—

The design for a hall-rack, as herein shown and described.

EDWIN P. KINGSBERRY.
